(57) **CLAIM**

The ornamental design for a digital camera, as shown and described.

DESCRIPTION

FIG. 1 is a top, front and right side perspective view of a digital camera showing my new design;

FIG. 2 is a top, rear and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a cross-sectional view thereof taken along line VIII-VIII of FIG. 3 and a portion defined by arrows A of FIG. 3, in which an internal structure thereof is not shown; and,

FIG. 9 is a cross-sectional view thereof taken along line IX-IX of FIG. 7 and a portion defined by arrows B of FIG. 7, in which an internal structure thereof is not shown.

The broken lines in FIGS. 8 and 9 depict portions of the digital camera that form no part of the claimed design. The dot-dash broken lines in FIGS. 8 and 9 represent the boundary lines of the enlarged cross-sectional view and form no part of the claimed design.
